UNITED STATES PATENT OFFICE.

ALBERT H. WALDECK, OF CLARKSBURG, WEST VIRGINIA.

DESIGN FOR A DISPLAY-RACK.

47,174.

Specification for Design.

Patented Mar. 30, 1915.

Application filed July 25, 1914. Serial No. 853,176. Term of patent 14 years.

To all whom it may concern:

Be it known that I, ALBERT H. WALDECK, a citizen of the United States, residing at Clarksburg, in the county of Harrison and State of West Virginia, have invented a new, original, and ornamental Design for Display-Racks, of which the following is a specification, reference being had to the accompanying drawing, forming a part thereof.

The figure is a perspective view of a display rack, showing my new design.

I claim:

The ornamental design for a display rack, as shown.

ALBERT H. WALDECK.

Witnesses:

H. C. BARTLETT,
H. H. JOHNSON.
